UNITED STATES PATENT OFFICE.

SAMUEL BOTTOMLEY, OF PROVIDENCE, RHODE ISLAND.

SERVETTE OR CATAMENIAL SACK.

1,332,597.

Specification of Letters Patent.

Patented Mar. 2, 1920.

Application filed June 22, 1918. Serial No. 241,375.

To all whom it may concern:

Be it known that I, SAMUEL BOTTOMLEY, a citizen of the United States, residing at Providence, in the county of Providence and 5 State of Rhode Island, have invented a new and useful Improvement in Serviettes or Catamenial Sacks, of which the following is a specification.

This invention relates to certain new and 10 useful improvements in a serviette or catamenial sack, with particular reference to a sack embodying a pad and a tubular casing therefor formed by securing the selvages of a length of fabric with a draw string.

15 The principal object of the invention is to incorporate the draw string in the selvages of the casing so that it will easily and conveniently be found when it is desired to pull the string from the casing.

20 A further aim resides in alternately weaving the draw string into the selvages for a distance and then floating it so that the floated portions may readily be grasped to pull the string.

25 The invention further resides in the provisions of a draw string differing in color from that of the casing whereby the string is quickly found.

In the drawings—

30 Figure 1 is an elevation of the improved serviette or catamenial sack.

Fig. 2 is an enlarged fragmentary view of the selvages of the casing, illustrating the draw string woven therein, and

35 Fig. 3 is a fragmentary cross sectional view of the article.

Referring more in detail to the drawings, the numeral 1 designates the tubular casing which is preferably formed of very loosely 40 woven or large mesh strip of fabric that is folded longitudinally and has its edge portions or selvages secured by the draw string 2. The pad 3 of absorbent material is disposed within the tubular casing and when 45 it becomes necessary to remove the pad the same is accomplished by pulling the string from the casing.

In the case of ordinary draw strings the ends are difficult to find and pick up. To 50 overcome the objections to the ordinary draw strings, I weave the draw string at spaced points, as at 4, in to the selvages whereby to provide free and unattached

lengths 5 of the draw string to be readily grasped for pulling on the same.

In weaving, the yarn or draw string is 55 carried into the loom so as to be incorporated with the casing in the following relation. The draw string is first woven into the material of the casing at one end for a 60 distance of two inches. The string is then floated, that is, not woven into the material but left free thereof, for a distance of three inches. It is next woven into the fabric selvages a distance of twelve inches, a distance 65 preferably as great as the length of the absorbent pad, again floated three inches and then woven four inches, floated three inches, woven twelve inches, floated three inches, woven four inches and so on throughout the length of the tube woven in the loom. The continuous length of casings is then 70 severed midway of each length of the four inch weave so that each casing will have two inches of woven draw string at each end 75 beyond the floated portion and a twelve inch weave intermediate the floated portions. Thus, the casings can be very cheaply and expeditiously manufactured or woven on a loom.

The pads are inserted in the casings in a manner somewhat similar to the filling of sausage skins, the long woven casing with its incorporated draw string being gathered over the nozzle of a machine adapted to 85 force the pads into the casing at predetermined or regular intervals as the casing is drawn from off the nozzle.

The draw string which is preferably colored so as to readily distinguish it from the 90 fabric, is wholly for the purpose of destroying the pad and casing separately. The floated portions permit the fingers to quickly find and grasp those portions of the draw string for pulling the string out from the 95 casing whereupon the latter may be laid open and the pad contents destroyed.

Having thus described my invention, what I claim as new and desire to secure by Letters Patent is—

100 A bandage comprising a pad, an enveloping casing formed of netting having a pair of parallel threads along and adjacent each of its opposite edges, said threads being of greater diameter than the body threads of 105 the netting and said edges being brought

together to form the enveloping casing in such a manner that the threads connecting said parallel threads will be intermeshed, and a drawstring passed through said intermeshed threads, parallel with said enlarged parallel threads, thus defining the seam and the position of the drawstring.

In testimony whereof I have signed my name to this specification in the presence of two subscribing witnesses.

SAMUEL BOTTOMLEY.
